Atty

UNITED STATES PATENT OFFICE.

HARRY B. WIER, OF PLAINFIELD, NEW JERSEY, ASSIGNOR TO WESTERN ELECTRIC COMPANY, INCORPORATED, OF NEW YORK, N. Y., A CORPORATION OF NEW YORK.

SOUND RECORDING AND REPRODUCING APPARATUS.

Application filed November 18, 1921. Serial No. 516,051.

To all whom it may concern:

Be it known that I, HARRY B. WIER, a citizen of the United States, residing at Plainfield, in the county of Union, State of New Jersey, have invented certain new and useful Improvements in Sound Recording and Reproducing Apparatus, of which the following is a full, clear, concise, and exact description.

10 This invention relates to apparatus for the recording and the reproduction of sounds, and particularly to electrical recording and reproducing means.

15 An object of the invention is to provide means for and methods of recording and reproducing sounds in their natural acoustical relation.

Other objects appear hereinafter.

20 In general the invention provides a pair of recording devices for simultaneously recording sounds, and a pair of reproducing devices for simultaneously reproducing the recorded sounds.

25 In previous systems for reproducing sounds, all sounds were heard as emanating from one source, and any sense as to their direction or relative location was lost in their reproduction. This invention provides for the reproduction of sounds so that they may be heard in their natural acoustical relation and thus render orchestral reproductions and others made by more than one performer more intelligible.

Referring to the drawings:

35 Fig. 1 represents apparatus for simultaneously making two records of the same sounds;

40 Fig. 2 represents apparatus for reproducing the records made by the apparatus shown in Fig. 1;

Fig. 3 represents apparatus for simultaneously recording the same sounds on two different records;

45 Fig. 4 shows apparatus for reproducing the sounds recorded by the apparatus shown in Fig. 3;

Fig. 5 is a sectional view of the reproducer;

50 Fig. 6 shows the form of stylus used in the recorder.

Fig. 7 shows the relation of two recorders or reproducers for making simultaneous traces on the same record or reproducing from such traces.

55 In Fig. 1, transmitters 8 and 9 for collect-

ing the sound waves are connected in series with batteries 10 and 11, and the primaries of induction coils 12 and 13 as in local battery circuits. The secondaries of coils 12 and 13 are connected to the electromagnetic recorders 19 and 20, respectively, which are energized from batteries 14 and 15. Sounds collected by transmitters 8 and 9 are simultaneously recorded by styluses 16 and 17 on a record 21, which rotates with an arbor 22 of a phonograph machine, not shown.

In Fig. 2 styluses 30 and 31 reproduce the sounds recorded on the record 21 in receivers 28 and 29 one for each ear such as a double head receiver. In series with the reproducers 32 and 33 and their respective receivers 28 and 29 are resistances 36 and 37 for the purpose of equalizing the volume of sound in receivers. It is obvious that a number of receivers, with their respective resistances, 75 may be connected in parallel across the reproducers 32 and 33.

In Fig. 3 transmitters 8 and 9 are connected to recorders in the same manner as in Fig. 1. In this case, however, traces are 80 made on two separate records 23 and 24 on arbors 26 and 27 coupled together by an adjustable coupling 25. In like manner the reproducing device shown in Fig. 4 differs 85 from that of Fig. 2 in that it is adapted to reproduce the sounds from the separate records made by the device shown in Fig. 3. The records are synchronized by any well-known synchronizing coupling 25, connected 90 between shafts 26 and 27.

In the recorder and reproducer illustrated in Figs 5, 6 and 7 the magnetic systems 32 and 33 may be the same as those of Patent 1,284,623 to H. C. Egerton, and pivotally supported on a bracket 40, carried by a 95 housing 41, by means of hinge members 39 and 44, and brackets 45 and 42. The bracket 45 and the hinge member 39 are adjustably secured together by a bolt 43 and an adjusting screw 51. One end of the adjusting screw 51 has threaded engagement with the hinge member 39 and the other end which is provided with a double flange for engaging each side of bracket 45 through slot 53, so that by loosening bolt 43 the 100 stylus 31 may be advanced or retarded by turning screw 51. Similar adjustment is provided for the other reproducer. This means of adjustment permits of the transmitters being placed in the most advanta- 110

geous positions for recording sounds, as either, or both recorders and reproducers may be adjusted so that the sounds reproduced will have their natural acoustical relation. Bracket 40 is provided with oppositely projecting L-shaped lugs 47 and 48 for limiting the movements of the magnetic systems when lifted clear of the record. The armatures 49 and 50 are provided with 10 off set portions for carrying the styluses as close to each other as possible.

It is evident that in cases where exceptionally high grade records are desired two such systems, employing amplifiers and high 15 quality transmitters, as disclosed in application, Serial Number 310,064, filed July 11, 1919, may be used. Also when necessary amplifiers may be connected between the reproducers and the receivers in any well- 20 known manner.

What is claimed is:

1. A binaural system for recording and reproducing sounds comprising a pair of transmitters for simultaneously collecting 25 the same sounds, a record, a double recorder for recording the sounds collected by each transmitter on said record, a double reproducer for reproducing the recorded sounds and a pair of receivers connected to said 30 reproducers whereby the sounds may be heard in their natural acoustical relation.

2. A binaural system for recording and reproducing sounds comprising a pair of transmitters for simultaneously collecting the same sounds, a record, a double recorder 35 for making parallel traces of the same sounds on said record, a double reproducer for reproducing the recorded sounds, means for adjusting the time interval between the sounds on each trace, means for adjusting 40 the phase relation between the recorded sounds whereby they may be reproduced in their true binaural relation, and a pair of receivers connected to said reproducers.

3. A binaural system for recording and 45 reproducing sounds comprising a pair of transmitters for simultaneously collecting the same sound, a record, a double electromagnetic recorder for recording the sounds in parallel traces on said record, means for 50 adjusting the phase relation of the recorded sounds, a double electromagnetic reproducer for reproducing the recorded sounds, means for adjusting the phase relation of the reproduced vibrations whereby the sounds 55 may be heard in their natural acoustical relation, and a pair of receivers connected with said reproducers.

In witness whereof, I hereunto subscribe my name this 15th day of November A. D., 1921.

HARRY B. WIER.
